CLAIM

I claim the ornamental design for a central processing unit for an automated teller machine, as shown and described.

DESCRIPTION

FIG. 1 is a front, right side perspective view of a central processing unit for an automated teller machine;

FIG. 2 is a back elevation view thereof;

FIG. 3 is a bottom plan view thereof;

FIG. 4 is a front elevation view thereof;

FIG. 5 is a side view thereof;

FIG. 6 is an opposite side view thereof; and,

FIG. 7 is a top plan view thereof.

The broken lines illustrate surface indicia and portions of the central processing unit for an automated teller machine which forms no part of the claimed design.
